CONCRETE FORM PANEL

Erwin A. Horn, Seattle, Wash., assignor, by mesne assignments, to I. F. Laucks, Inc., Seattle, Wash., a corporation of Washington

Application May 22, 1940, Serial No. 336,640

5 Claims.

(Cl. 25—131)

The present invention relates to improved concrete form units which are both durable for repeated use and suitable for a wide range of construction jobs.

The common method of constructing concrete forms is to build them in place with the pressure receiving face supported by vertical stud members which are usually 2 x 4's placed on edge and, in turn, supported at their rear edges by walers in the form of horizontal timbers which contact the rear edges of a number of studs. The facing material, either boards or panels, is generally nailed to the studs and the walers are then bolted through the studs onto the forms. This construction results in a thick panel which is so awkward and difficult to handle or store as a unit, that it is generally entirely torn apart as the first step in stripping the forms. Even when the studs are not removed from the facing, the walers have to be taken off when the forms are stripped. If it is desired to re-erect the forms for another use, the procedure is reversed and the walers reattached after the forms have been set up in their new location. It is ordinarily impractical to replace the walers in their exact original position so usually every use requires that new holes be bored through both walers and form faces. This removal and reattachment of the walers constitutes one of the major items of labor in assembling and dismantling concrete forms and the repeated removals of the walers also shorten the life of both walers and covering. As a result, re-use of such forms is frequently impractical and in a large proportion of jobs the forms are specially built and then destroyed after a single use. It is also often necessary to build forms in restricted spaces to reduce excavation or to prevent interference with adjacent structures. For this purpose, less bulky forms would be advantageous. It would also frequently prove a great economy to have forms which are relatively thin, yet sturdy, and capable of both removal intact and reinstallation as complete units on other jobs.

The principal object of the present invention is to provide a form which has adequate stiffness so as to require a minimum of bracing and yet is relatively thin and compact and which will provide the combination of features which adapts it for a large number of reuses. Another object is to provide a form which is particularly adapted for use as a unit, so that a number of duplicate or similar units can readily be combined and assembled to meet the requirements of a particular job and then be easily removed

and recombined at another location to meet the particular requirements of the next job and to have these units of such sturdy construction that a great number of reuses will be feasible.

This calls for a combination of features not hitherto available. First, there must be a high degree of inherent stiffness to resist deflection and eliminate external bracing as far as possible. The forms must also be as thin as possible, so that the units can be handled easily when setting them up and when stripping them from the concrete and both front and rear faces must be free from projections so that they can be piled compactly in storage. It is highly desirable that such forms have smooth pressure faces of a durable nature, so as to produce smooth concrete walls, and that the faces be treated so as to strip cleanly both for the sake of the walls and to eliminate damage to the faces in cleaning. They should also be adapted for unit construction, so that a stock of units in a few sizes can be combined to provide forms for a wide range of jobs. The units also should be capable of ready attachment both laterally along one face of the wall, and through the intervening concrete, to tie the two sets of enclosing walls together to resist the pressure of pouring and produce walls of even thickness.

To the accomplishment of the foregoing and related ends, the invention, then, comprises the features hereinafter fully described, and particularly pointed out in the claims, the following description setting forth in detail certain illustrative embodiments of the invention, these being indicative, however, of but a few of the various ways in which the principle of the invention may be applied.

I have devised an improved concrete form which meets these requirements. In practicing my invention, I prefer to use resin bonded Douglas fir plywood in order to secure durability for the pressure receiving face which contacts the concrete. To prevent the concrete sticking to the surface of the plywood and also to make the surface more durable, I prefer to treat the plywood with one or two coats of a water-resistant synthetic resin sealer of a highly penetrating character. A very suitable sealer is described in United States Patent No. 2,150,188, issued to Rippey and Dike. However, I do not restrict my invention to the use of plywood surfacing, but, in some instances, may use a compressed artificial board having a dense surface and which has been treated either in manufacture or subsequently, so as to produce a smooth, non-sticking surface.

For the supporting frame, I ordinarily use dimension lumber in the form of studs and walers. A characteristic feature of my invention is that both the studding and the walers are adhesively attached with a water-resistant glue, for example, a water-resistant casein glue to the rear surface of the facing panels. The studs which may ordinarily be 2 x 4's or 2 x 6's are placed on edge and glued onto the plywood panels. Nails may be used in place of clamps to hold the surfaces in contact while the glue is setting, the nails afterwards being withdrawn, if desired. The spacing of the studs may be varied according to the conditions, but with light forms of thin walls are usually placed on 16" centers. In designing the stud supports, I make the studding relatively short and at the location where waler supports would be required along the back edge of the studs in the ordinary type of forms, I insert the waler timbers which may be 4 x 4's for 2 x 4 studs, or 6 x 6's for 2 x 6 studs, between the ends of adjacent rows of studs attaching the ends of the studs to the walers firmly and gluing the walers to the facing. I then provide means for tying the walers together against the thrust of the studs and preferably provide that the tying means does not project outwardly from the rear surface of the form. In some instances, I provide as a tie a second plywood skin glued onto the rear face of the forms, while, in other instances, I may use gusset plates or metal rods or some similar means for tying which is of a character adapted to be located entirely within the studding spaces.

In the accompanying drawings, a plurality of preferred embodiments of the present invention are illustrated, but it must be understood that the invention is not limited to the details of construction disclosed, as many modifications and other embodiments of the invention will readily occur to one skilled in the art.

In the drawings:

Figure 1 is a perspective view of a plurality of panel units in assembled relation.

Figure 2 is a diagrammatic plan view of a monolithic concrete structure, showing a preferred arrangement of form units.

Figure 3 is an elevation, partly in section, of a panel unit, similar to the one shown in Figure 1.

Figure 4 is a horizontal section on line 4—4 of Figure 3.

Figure 5 is a sectional detail on line 5—5 of Figure 3.

Figure 6 is a horizontal sectional detail of a modification.

Figures 7 and 8 are end and side views of a coupling element.

Figures 9 and 10 are end and side views of an angle bracket.

Figure 11 is a vertical sectional view on line 11—11 of Figure 3.

Figure 12 is a vertical sectional detail on line 12—12 of Figure 3.

Figure 13 is an elevational detail of a preferred form of corner connection.

Figure 14 is a fragmentary elevation and partial section of a modified form of panel structure.

Figure 15 is a horizontal section of the construction shown in Figure 14.

Figure 16 is an elevational view, partly in section, of another wall construction, and

Figure 17 is a horizontal sectional view of the same.

Referring to Figure 2, the present invention has been found particularly useful in connection

with the building of large, heavy monolithic concrete structures, such as bridge piers and the like. For instance, forms of the type shown in Figures 1, 3 and 4 were used in building the piers for the 2,800 foot suspension bridge now being built by the Washington Toll Bridge Authority across the Narrows of Puget Sound, Tacoma, Washington.

In accordance with the present invention, a plurality of form units are assembled in groups 10 of three, four or any other convenient number, to define hollow spaces or cells around which the concrete is poured. Thus, groups of four units 20, 21, 22 and 23 may be assembled in edge to edge relation and the groups or sets positioned with 15 their manually facing walls spaced apart in parallel relation to provide spaces in which concrete 25 may be poured and packed. After the concrete has set somewhat, but preferably before it has completely hardened, the tie rods connecting the 20 groups of panel members, described below, are removed and the forms lifted. They are then reconnected and more concrete is poured to continue the vertical building-up of the concrete structure.

25 For this type of work, panel units of the type shown in Figures 1—4 are preferred. These members are made up of a smooth, outer facing layer 27 of such material as plywood, a reinforcing framework 28 and, preferably, an inner layer of 30 sheet material 29 which also is preferably plywood material. The individual elements of the framework may be glued to each other and to the inner and outer plywood coverings, so that a strong, rigid, internally reinforced, smooth-faced, 35 unitary panel element is provided.

As shown in Figures 3 and 4, the internal framework comprises vertical edge members 30, 31, extending the full height of the panel and vertical, intermediate members 32, 33, 34, all of 40 which are relatively heavy wooden timbers. Between the elongated vertical members or walers 31, 32, etc., there are a plurality of horizontal stud members 35, having their ends 36 disposed in sockets 37, formed in the walers. As shown in Figure 5, the sockets 37 have inclined bottoms 45 and the ends 36 are cut on similar inclined planes, with the result that pressure applied to the studs from outer face 27 simply wedges the studs more tightly between the walers and prevents any substantial movement therebetween. The ends of the studs are preferably secured in the sockets by glue. It is seen also that the inclined ends of the studs and the inclined bottoms of the sockets provide a greater gluing area than would be the case if the studs were cut square.

55 As an alternative method, the studs 35a (Fig. 6) may be secured to the vertical walers 32a by ring connectors 39 embedded respectively in the ends of the studs and the side faces of the walers. Moreover, the ring connectors 39 may be used to secure the end faces of the walers to the horizontal top and bottom frame members 40, 41.

In the preferred embodiment, however, the ends of the studs 35 are inclined, as shown in Figures 3 and 5. Any tendency to relative movement between the studs and the walers would serve to move the walers apart, relative to each other, but this tendency is effectively resisted by the outer plywood sheets glued thereto, or by other interconnecting means, such as bolts or the like.

70 The inner plywood layer 39 is provided with a plurality of openings 42 which give access to socket members 43, set in the vertical frame members 33 and carrying bolts 44 which may be connected to tie rods 45, to secure the groups or

sets of panel elements to each other, as indicated in Figure 1. Preferably, as shown in Figure 5, the bolts 44 are internally threaded to receive the threaded ends of the tie rods.

The inner facing layer 29 is also provided with a plurality of vertically aligned openings 41 disposed above the horizontal studs 35 carrying tread blocks 48 and providing a ladder for use by the workmen.

At its upper end, each panel carries a bevelled edge strip or block 50, secured to the upper member 40 of the frame by bolts 51 or the like. Lifting bails 52 extend downwardly through the bevelled strip 50, the upper edge frame member 40 and certain of the studs 35, to which they are secured by nuts 53. At its lower end, the frame carries a lower, bevelled edge strip 55, secured to the frame by bolts 56 and having its undersurface notched at suitable points, where angular brackets 57 are secured by screws or the like projecting through openings 58 therein. These angle members provide spaces for bolts 59, which project through openings in an edge plate 60 and are connected to internally threaded coupling elements 61, which, in turn, are connected to transverse tie rods 62. A rib 63 on the outer surface of each coupling element facilitates engagement by a pipe wrench or the like.

Similar bolts 65 extend through the upper horizontal frame member 40, where they are connected to coupling members 61 and tie rods 62, as shown in Figure 11.

The vertical edge members 30, as shown in Figure 4, and the walers 31 are preferably provided with bevelled faces, so that, when two panel units are secured to each other in right angular relation, by metal straps 67, bolted together, the bevelled faces lie in parallel planes. The sections, thus secured together by the tension-resisting straps 67, may be made rigid by the use of any appropriate pressure applying devices, such as pairs of wedges 68, the lower of which may be supported against downward movement by a wood strip glued to the bevelled face of one unit, as indicated in Figure 13. Of course, the invention is not limited to the use of wedges as a means for applying a separating force to the form units to place the straps 67 under tension and provide a rigid connection therebetween, as any equivalent device may be employed, such as screw-threaded or cam-actuated expanders. By the use of such devices and the connecting straps 67, a plurality of the panel-like form units may be joined together in extremely tight, rigid relation. However, they may be slightly collapsed inwardly, relative to each other, by disconnecting the tension straps and removing or contracting the expanding devices, when it is desired to remove the units from a cast wall section.

The advantages of the panel-like form units just described are numerous. The internal reinforcing frame cooperates with the surface plies to provide a rigid, non-bending unitary structure. The water-resistant glue bond between the surface plies and the framework is far stronger than spikes or nails and relative movement of the various parts is impossible. Any bending stress or any tendency for relative movement between the studs and the walers results in placing the inner plywood plies under tension. However, since material of this kind has tremendous tensile strength, such distortion and displacement of the parts is effectively resisted.

When the forms of the type shown in a plan, such as is disclosed in Figure 2, are being in-

stalled, it is usually necessary to excavate from inside the forms, by the use of a "clam shell" scoop or the like, operating within the cell defined by a group of panels. Hence, it is important that, in this space, there be no laterally projecting obstructions, which might interfere with the work of the clam shell. The forms of the present invention are particularly adapted to accomplish this advantage, since all of the reinforcing members are disposed within the panels and are concealed by the inner face ply.

In the forms of the invention shown in Figures 14-17, the walers 10 are disposed horizontally and the studs 71 extend vertically between the walers and between the walers and the top and bottom strips 72, 73. Preferably, the ends of the walers are inclined and are set in sockets having inclined bottoms facing outwardly, as previously described. As shown in Figure 14, an inner face ply 74 of plywood or the like may be adhesively united to the walers and studs, or, as suggested in Figure 16, bolts 75 may be employed, or both may be used in the same installation. Preferably the form in accordance with this modification is made up in a plurality of sections which may be joined together in end-abutting relation by means of rods 76 extending through appropriate apertures in the vertical studs and defined by washers 77 or the like. A wedge 78 disposed in a slot in the rod may be employed to draw the sections tightly together, access being had to the wedge by appropriate openings in the plywood covering remote from the surface which contacts the concrete.

As indicated in Figure 17, the end panel section 89 terminates at one edge in a vertical member 81 having a bevelled portion adapted to mate with a similar vertical member 82 of the next section, whereby the sections may be joined together in right angular relation. The outer plywood coverings 83, 84 project beyond the inner plies 85 and, at the corner, a vertical finishing strip 86 is interposed. Hence, when the concrete is poured against the outer plies 83, 84, a clean, sharp corner is formed.

The structure shown in Figure 15 is adapted to form the outer surfaces of a corner and may be used in outwardly spaced relation to the structure shown in Figure 17. Hence, the inner panels 87, 88 are the faces which contact the concrete, and the two sections may be joined together by a suitable wood strip 89.

Of course, any number of central sections 96 may be joined together in end to end relation, by means of coupling bars 76 or the like, and at the corners of the foundation, end sections 80 or 88 may be employed.

These types of forms are preferred for ordinary building operations, such as for foundations for homes and buildings. By using various combinations of different types of units, a wide variety of wall plans may be devised.

I claim:

1. In a concrete form, a unitary panel structure comprising a smooth, continuous, plywood sheet adapted to contact the concrete and to receive pressure therefrom, and a wooden supporting frame behind said sheet including stud members and waler members adhesively secured to the rear face of the sheet, the ends of the studs being disposed on rearwardly facing inclined planes and being secured in abutting relation upon similar, oppositely inclined surfaces carried by the walers, and means secured to the walers to prevent relative separation thereof,

2. In a concrete form, a unitary panel structure comprising a smooth, continuous sheet adapted to contact the concrete and to receive pressure therefrom, and a supporting frame for said sheet including stud members and waler members both adhesively secured to the rear face of said sheet, the ends of the studs being disposed on rearwardly facing inclined planes and being secured in abutting relation upon similar oppositely inclined surfaces associated with the walers, and a second sheet glued to the rear faces of the walers and studs to prevent relative separation of the walers.

3. In a concrete form, a panel unit comprising smooth, continuous covering sheets on both front and rear pressure and non-pressure receiving faces thereof, a frame comprising waler members secured to the sheets, and stud members having their ends on rearwardly facing inclined planes wedged between the sides of the walers, and tie bolts connecting the walers to assist said covering sheets in resisting separation of the walers.

4. In a concrete form, a unitary panel structure comprising a plywood sheet adapted to contact the concrete and to receive pressure therefrom, a second plywood sheet spaced rearwardly therefrom, and a pressure resisting framework between the sheets and adhesively united there-

to, said framework comprising a plurality of spaced parallel walers extending substantially entirely across one dimension of the sheets, and stud members disposed transversely of the walers and having their ends in abutting relation to the sides of the walers, the ends of the studs being cut on rearwardly facing inclined planes and disposed in abutting relation against oppositely inclined surfaces of the walers, said plywood sheets serving to resist displacement of the walers relative to each other and relative to the studs.

5. In a concrete form, a unitary panel structure comprising a plywood sheet adapted to contact the concrete and to receive pressure therefrom, a second plywood sheet spaced rearwardly therefrom, and a pressure resisting framework between the sheets and adhesively united thereto, said framework comprising a plurality of spaced parallel walers extending substantially entirely across one dimension of the sheets, and stud members disposed transversely of the walers and having their ends in abutting relation to the sides of the walers, the ends of the studs being cut on rearwardly facing inclined planes and disposed in abutting relation against oppositely inclined surfaces of the walers, and bolts connecting the walers to resist displacement thereof relative to each other and relative to the studs.

ERWIN A. HORN.
